UNITED STATES PATENT OFFICE

JAMES H. GRIFFIN AND ELLSWORTH E. TIERS, OF CLAY CENTER, KANSAS

ROTARY SNOWPLOW

Application filed May 21, 1927. Serial No. 193,319.

Our invention relates to rotary snow plows and one object is to provide a machine which will effectively clear the snow from the highways in order that the latter can be kept open 5 for traffic during the winter season.

A further object is to provide a machine of this character which can be pushed forwardly over a highway by a team or a tractor and will collect and discharge the snow clear of either 10 or both sides of the highway, as preferred.

Other objects will hereinafter appear, and in order that the invention may be fully understood reference will now be had to the accompanying drawings, in which:

15 Fig. 1 is a front elevation of the machine with a portion of the housing thereof broken away.

Fig. 2 is a plan view partly in section on line 2 of Fig. 1, showing the machine coupled 20 to the forward portion of a tractor.

Fig. 3 is a side elevation of the machine with a portion of the mechanism nearest to the observer removed.

Fig. 4 is a fragmentary vertical section on 25 line 4—4 of Fig. 1.

Fig. 5 is a detail of one of a pair of valves.

Fig. 6 is a broken perspective view of a portion of the mechanism for operating the valves.

30 Referring in detail to the different parts, 2 designates a suitable frame which is mounted upon an axle 4 carried by a pair of ground wheels 6. The spindles 8 of the ground wheels 6 are connected by pivots 10 to the ends of the 35 axle 4 and provided with steering arms 12, the foregoing construction being similar to the well-known steering mechanism on the front wheels of motor vehicles. When a tractor A is employed for advancing the machine 40 crossed steering rods 14 are pivotally connected to the steering arms 12 and the front axle B of the tractor, as shown by Fig. 2, so that the tractor will steer the snow plow while propelling the latter.

45 16 designates a housing which is secured to the front portion of the frame 2 by suitable means such as brackets 18. The front wall of the housing 16 constitutes a snow collector 20 which has a centrally-disposed forwardly-projecting divider 22 for directing the snow

to a pair of oppositely-disposed circular inlets 24 and 25 formed in said housing 16. The divider 22 is assisted in directing the snow to the circular inlets 24 and 25 by a horizontally-disposed blade 26 extending forwardly 55 from the lower portion of the collector 20. The upper portion of the housing 16 is provided with oppositely-disposed discharge chutes 28 and 30 which communicate at their lower portions with the circular inlets 24 and 25, respectively.

32 and 34 designate a pair of rotors arranged within the circular inlets 24 and 25 and consisting of blades 36 and 38 mounted upon shafts 40 and 42 arranged concentrically within said inlets 24 and 25, respectively. The shafts 40 and 42 are journaled in gear casings 44 and 46 secured to the forward portion of the frame 2, and said shafts 40 and 42 are provided at their rear ends with 60 bevel gears 48 and 50, respectively.

The bevel gears 48 and 50 are adapted to be driven independently of each other, and either in the same direction or in opposite directions by the following mechanism. 52 65 designates a main shaft extending transversely to the shafts 40 and 42 and journaled in the casings 44 and 46. 54 designates a clutch member slidably mounted upon said main shaft 52, but caused to rotate therewith through the usual spline, not shown. 58 and 60 designate two bevel gears loosely mounted upon the main shaft 52 and intermeshing with the bevel gear 48. Said bevel gears 58 and 60 have clutch members with 70 which the clutch members 54 may be alternately thrown in and out of gear by means of a lever 62 operably connected at its outer end to one end of a rod 64, which latter is operably connected at its opposite end to 75 a crank 66 fixedly mounted upon a rock-shaft 68 journaled in bearings 70 and provided with a hand lever 72.

76 designates another clutch member similar to the clutch member 54 and slidably mounted upon the drive shaft 52, but caused to rotate therewith through the customary spline, not shown. 78 and 79 designate two bevel gears intermeshing with the bevel gear 50 and loosely mounted upon the main shaft 80

52. Said bevel gears 78 and 79 have clutch members with which the clutch members 76 may be alternately thrown in and out of gear by a lever 80 pivotally connected at one end to the clutch member 76 and at its opposite end to a connecting rod 82 which is operably connected to a crank 84 fixedly mounted upon a rock-shaft 86 journaled in bearings 88 and provided with a hand lever 90.

10 94 and 96 designate valves provided at their upper ends with forwardly projecting flanges 95 and 97 for partially closing communication between the circular inlets 24 and 25 and the discharge chutes 28 and 30, respectively. Said valves 94 and 96 are fixed to sleeves 98 and 100 rockably mounted upon the forward portions of the gear casings 44 and 46 and provided with arms 102 and 104 which are connected to cranks 106 and 108 through the intermediary of connecting rods 110 and 112, respectively. The cranks 106 and 108 are fixedly mounted upon pivots 114 and 116 journaled in bearings 118 and 120, respectively, secured to the lower portion of 25 a blower housing 122 mounted upon the upper rear portion of the housing 16 and communicating with the chutes 28 and 30 through an opening 124. The housing 122 is equipped with a suitable fan or blower 126 which creates a blast of air for assisting the rotors 32 and 34 in discharging the snow through the chutes 28 and 30, respectively.

30 128 and 130 designate two independent sets of deflectors for controlling the blast of air created by the blower 126. Said deflectors 128 and 130 are mounted adjacent to the opening 124 and each set consists in the present instance of a group of three blades. One blade of one group is mounted upon the pivot 114 and one blade of the other group is mounted upon the pivot 116. The remaining blades of the deflectors 128 and 130, are mounted upon pivots 132 and 134, which are operably mounted in the upper and lower portions of the blower housing 122. Each group of blades 128 and 130 are operably united by connecting rods 138 and 140, respectively, so that the blades of each group will operate in unison.

40 50 The blower 126 is fixedly mounted upon a shaft 142 journaled in the rear portion of the housing 122 and provided with a fixedly mounted bevel gear 144 intermeshing with a bevel gear 146 mounted upon the upper end of a vertical shaft 148 provided at its lower end with a fixedly mounted bevel gear 150 intermeshing with a bevel gear 152 fixed upon the drive shaft 154 of a suitable motor 156, which latter is carried upon a platform 157.

55 60 65 The drive shaft 154 in addition to being equipped with the bevel gear 152, is also provided with a fixedly mounted bevel gear 158 which intermeshes with and drives a bevel gear 160 fixedly mounted upon the main shaft 52. In order that the blower 126 may

be thrown in and out of gear with the motor 156, the bevel gear 146 is loosely mounted upon the shaft 148 and provided with a clutch member 149 adapted to be driven by a companion clutch member 151 slidably mounted upon the shaft 148, but rotatable with the latter through the intermediary of the usual spline, not shown. The clutch member 151 is controlled by a bell-crank 153, which is actuated by a rod 155.

The two groups of air deflectors 128 and 130 are adjusted to the positions shown by Fig. 2, so that the deflectors 128 will direct a portion of the blast from the blower 126 outwardly through the chute 28, while the deflectors 130 direct the remainder of the blast outwardly through the chute 30, thereby cooperating with the rotors 32 and 34 and the valves 94 and 96 in throwing the snow to 10 opposite sides of the highway as stated. If it is desired to throw all of the snow outwardly through the chute 28, the valve 94 and the deflectors 128 are left in the positions above-mentioned, but the valve 96 is adjusted to 15 close communication between the right-hand side of the inlet 25 and the chute 30, while the deflectors 130 are adjusted in a similar position to the deflectors 130 through the intermediary of their connection with said 20 valve 96. The mechanism for driving the rotor 38 is also adjusted for driving said rotor in reverse direction to the associate arrow *a*. On the other hand if all of the snow is to be discharged from the chute 30, 25 the valve 96 and the deflectors 130 are left in their initial position while the valve 94 is adjusted to close communication between the left side of the inlet 24 and the chute 28. While thus being adjusted said valve 30 94 through the intermediary of the connecting mechanism adjusts the deflectors 128 in the same direction as the deflectors 130, while the mechanism for driving the rotor 32 is adjusted to drive the latter in a reverse direction 35 to the associate arrow *a*.

In Fig. 3, we have shown a tongue 200 which is coupled to the snow plow in place of the tractor A and mounted at its rear end upon a tiller wheel 202. A team may be 40 hitched to said tongue 200 for pushing the snow plow forwardly over the highway. Means for adjusting the housing 16 vertically is provided in the form of a connecting rod 203, which is operably secured at its lower 45 end to a hand lever 204 and at its upper end to the rear portion of the blower housing 122. By throwing said lever 204 forwardly the housing 16 is lowered close to the surface of the road, and conversely when said lever 204 50 is drawn backwardly it raises the housing 16 so that it will leave sufficient snow upon the highway for coasting and other winter sports. The housing 16 is permitted to move 55 vertically by rocking the frame 2 around the centers of the ground wheels 6.

From the foregoing description it is apparent that we have provided a snow plow embodying the advantages above pointed out, and while we have shown a described and preferred embodiment of the invention we reserve all rights to such changes and modifications as properly fall within the spirit and scope of the invention as claimed.

Having thus described our invention, what

we claim and desire to secure by Letters Patent is:

1. In a machine of the character described, a housing having inlets and oppositely-disposed discharge chutes communicating with said inlets, a rotor associated with each inlet, a valve associated with each inlet for partially closing communication between the latter and either of said discharge chutes, and independent mechanisms for operating each 75 valve.

2. In a machine of the character described, a housing having an inlet and oppositely-disposed discharge chutes communicating with said inlet, a rotor associated with said inlet, mechanism for driving said rotor in reverse directions, a blower communicating with said discharge chutes, and air deflectors interposed between said blower and said discharge chutes.

3. In a machine of the character described, a housing having an inlet and oppositely-disposed discharge chutes communicating with said inlet, a rotor associated with said inlet, mechanism for driving said rotor in reverse directions, a blower communicating with said discharge chutes, two groups of adjustable air deflectors interposed between said blower and said discharge chutes, and independent mechanisms for adjusting each group 85 so that the latter may deflect a blast from the blower into both chutes or deflect said blast into either chute.

4. In a machine of the character described, a housing having inlets and oppositely-disposed discharge chutes communicating with said inlets, a rotor associated with each inlet, a valve associated with each inlet for partially closing communication between the latter and either of said discharge chutes, a blower 100 communicating with said discharge chutes, two groups of adjustable air deflectors interposed between said blower and said discharge chutes, independent mechanisms for adjusting each group 105 so that they may deflect the blast from the blower into both chutes or into either chute, and mechanisms for actuating the valves simultaneously with said groups.

5. In a machine of the character described, a housing having an inlet and oppositely-disposed discharge chutes communicating with said inlet, a rotor associated with said inlet and including a plurality of blades, a blower 115 communicating with said housing and adapted to force air through the discharge chutes, and a container adapted to discharge a lubricant in front of said blower.

6. In a machine of the character described, a housing having inlets and discharge chutes, rotors mounted in said housing, a blower communicating with said housing, and air deflectors interposed between said blower and the discharge chutes.

7. In a machine of the character described, a housing having an inlet and a discharge 120

chute communicating with said inlet, means for forcing a blast of air through said discharge chute, and a container for discharging a lubricant into said air blast.

5. 8. In a machine of the character described, a housing having inlets and discharge chutes communicating with said inlets, rotors located in said inlets, shafts upon which said rotors are mounted, sleeves rockably mounted on 10 said shafts, bearings in which said shafts are mounted, sleeves rockably mounted on said bearings, valves fixed to said sleeves and arranged to partially close communication between the inlets and the respective chutes, and independent mechanisms for rocking said sleeves.

15. In testimony whereof we affix our signatures.

JAMES H. GRIFFIN.
ELLSWORTH E. TIERS.
